PIE DISPLAY AND WARMING CABINET

James C. Schindler, Naperville, Ill., assignor to McDonald's System, Inc., a corporation of Illinois

Filed Apr. 1, 1969, Ser. No. 16,549

Term of patent 14 years

Int. Cl. D7—04
U.S. Cl. D81—10

FIG. 1

FIG. 2

FIG. 3

I claim:

The ornamental design for a pie display and warming cabinet, substantially as shown.
